United States Patent Office

Des. 208,987
Patented Oct. 24, 1967

208,987

GARDEN CULTIVATOR

Howard A. Anderson, Pittsburgh, Pa., and Henry J. Rosendall, Grand Rapids, Mich., assignors to Bissell Inc., Grand Rapids, Mich., a corporation of Michigan

Filed Aug. 24, 1966, Ser. No. 3,567

Term of patent 14 years

(Cl. D35—2)

FIG. 1.

FIG. 2.

FIG. 3.

FIG. 4.

FIGURE 1 is a side elevation of a garden cultivator, showing the new design, the opposite side being a mirror image;

FIG. 2 is a top plan view thereof, the bottom plan view being a mirror image;

FIG. 3 is an end view thereof, taken on line 3—3 of FIG. 2; and

FIG. 4 is a bottom plan view thereof.

We claim:

The ornamental design for a garden cultivator, substantially as shown and described.
